UNITED STATES PATENT OFFICE

2,499,748

DEVICE FOR WEATHERPROOFING TEXTILE
FABRIC ARTICLES

A. De Vere Harnett, Racine, Wis.

Application July 26, 1946, Serial No. 686,337

6 Claims. (Cl. 91—46)

1

The present invention relates to a device or machine for weatherproofing textile fabric articles by immersing them in a suitable solution containing a water-repellent material.

In recent years, there have been commercially developed various water-repellent materials with which textile fabric articles such as clothes may be impregnated to prevent them from absorbing moisture. Articles of clothing and particularly outer garments such as topcoats and the like can be made into effective raincoats or water-repellent garments by impregnating the garment with this material. On such water-repellent material is of a wax-like nature and is usually applied by blending it in a suitable solvent such as naphtha or the like, which solvent is extracted after application leaving the water-repellent material in the garment.

A water-repellent solution of the type referred to above must be maintained in a heated condition for satisfactory operation and furthermore to maintain a uniform solution, it is necessary to agitate the liquid at frequent intervals. The solvent for the water-repellent material is generally a skin-irritant and consequently, it is desirable to provide a device or apparatus for weatherproofing textile fabric articles in the above-mentioned manner in the use of which it is not necessary for the operator to touch the impregnated articles or the solution, thereby to prevent injury to the operator's skin.

Accordingly, it is an object of the present invention to provide a device or machine for weatherproofing textile fabric articles embodying the desirable features enumerated above.

It is another object of the present invention to provide a new and improved device or machine for weatherproofing textile fabric articles by immersing them in a water-repellent solution.

It is a further object of the present invention to provide a device or machine for weatherproofing textile fabric articles which is of simple and sturdy construction and has a higher output capacity than prior art devices.

Still a further object of the present invention is to provide a machine or device for weatherproofing textile fabric articles which includes means for heating and agitating the solution with which the articles are impregnated and in the use of which it is unnecessary for the operator to handle the articles.

Further objects and advantages of the present invention will become apparent as the following description proceeds and the features of novelty which characterize this invention will be pointed

out with particularity in the claims annexed to and forming a part of this specification.

For a better understanding of the present invention, reference may be had to the accompanying drawings in which:

Fig. 1 is a perspective view of a machine or device embodying the present invention;

Fig. 2 is a view similar to Fig. 1 with the cover of the device removed and showing the article holding baskets in two different positions assumed during operation of the device;

Fig. 3 is a top plan view of the device of Fig. 1 with the cover removed and with the article container in position for soaking the textile fabric articles in the liquid impregnant;

Fig. 4 is a sectional view taken on the line 4—4 of Fig. 3;

Fig. 5 is a sectional view taken on the line 5—5 of Fig. 4, assuming that Fig. 4 shows a complete device;

Fig. 6 is a view partly in section of a machine for weatherproofing textile fabric articles embodying a modification of the present invention;

Fig. 7 is a perspective view of a modification of the present invention with the cover in a predetermined position; and

Fig. 8 is another perspective view of the modification of Fig. 7 with the cover thereof removed.

Referring now to the drawings, there is illustrated a device or machine constructed in accordance with the present invention generally designated at 9 and comprising a unitary tank-like structure 10 having a substantially rectangular section. It should be understood that the particular shape of the tank-like structure 10 forms no part of the present invention and the rectangular structure illustrated is by way of example only. The rectangular structure 10 includes a fluid chamber 11 which is defined by the walls of the rectangular structure 10 and a bottom member 12 having crossed creases 13 so as to facilitate draining through an opening 14' located at the intersection of the creases 13 centrally of the fluid chamber 11. As will be apparent from Fig. 4 of the drawings, the bottom 12 slopes toward the central opening 14'.

In order movably to support the tank-like structure 10, there is provided a portion 10' of the rectangular structure which extends below the bottom 12 of the fluid containing chamber 11 so as effectively to provide a skirt which performs two functions. First it effects streamlining of the device or unit 9 and secondly, it provides a means for holding a plurality of supporting casters 15 and 16. The casters 15 associated with one end

of the structure 18 are not swiveled and are fastened to the skirt 10' as by welding or any other suitable means. The reason these casters are not swiveled will become apparent as the following description proceeds. The casters 18, on the other hand, which are mounted at the two corners opposite from the casters 15 are swiveled as indicated at 17, whereby the device 9 may readily be moved about in any desired manner. It will be understood that for certain applications the casters 15 and 18 may be omitted entirely. Such an arrangement is shown in Figs. 7 and 8 of the drawings.

For the purpose of maintaining the liquid impregnant in the tank or fluid chamber 11 in a heated condition as is desirable in order to obtain satisfactory waterproofing of the textile fabric articles, there is provided a suitable heating coil 18 positioned within the fluid containing chamber 11 closely adjacent the bottom 12 thereof. This heating coil may comprise any suitable heating means such as an electrical heating device, but as illustrated, preferably comprises a fluid coil to which a suitable heating medium such as steam or the like may be supplied. As illustrated in the drawings, the heating coil 18 extends to suitable openings 18a provided in one of the side walls of the fluid containing chamber 11 and terminates in suitable connections 18 and 20 which extend outside this chamber and to which a suitable source of heating medium such as steam or the like, not shown, may be connected. It should be understood that suitable control means, not shown, such as an automatic thermostatic control or manual control means for controlling the temperature of the liquid impregnant in tank 11 by controlling the admission of heating medium to the coil 18 will be provided. Preferably the chamber 11 when in use is filled with the solution containing the water-repellent material to the level indicated by the line 21 in Fig. 4 of the drawings. A suitable temperature indicating device 22 is provided so that the operator may know that the temperature of the solution in the chamber 11 is initially at its proper value and is maintained at this value for best operation as determined by the directions supplied with the particular water-repellent impregnating material used. Preferably, openings such as 18b, which are duplicates of the openings 18a, are provided in the side wall of the fluid containing chamber 11 opposite the wall containing the openings 18a. With this arrangement, it is possible to make external connections to the heating coil 18 from either side of the chamber 11, thus permitting either side of the unit 9 to be positioned against a building wall. It will be understood that the particular openings such as 18b which are not used in making connections with the heating coil 18 are closed by suitable interchangeable closure means which can also be used to close the openings 18a instead of the openings 18b.

In order to agitate the solution comprising the water-repellent impregnant contained in fluid chamber 11, there is provided a suitable agitator 23 which is specifically illustrated as a screw or propeller but which may assume any desirable form. As illustrated, the agitator 23 is mounted on a vertical shaft 24 rotatable in suitable bearing means 25 supported within the fluid chamber 11. The bearing means 25 are supported from a partition 26 which effectively divides the fluid containing chamber 11 into two chambers specifically designated as 11a and 11b, respectively.

This partition extends only partially toward the bottom 12 of the fluid chamber 11 leaving an aperture 11c through which the liquid contained in the sections 11a and 11b may freely flow from one section to the other. As illustrated, the agitator 23 extends beneath the partition 26 so as effectively to agitate the liquid in both sections 11a and 11b of the fluid chamber 11. A suitable removable crank 27 is provided for operating the agitator 23. It should be understood that the agitator 23 need only be periodically operated. Also, and as will become apparent from the following description, the operation of the device in waterproofing textile fabric articles will cause a predetermined agitation of the liquid impregnant exclusive of the operation of agitator 23.

For the purpose of draining the solution from the fluid chamber 11, the drain opening 14' in the bottom wall 12 is connected to a suitable swiveled T connection 31 best shown in Figs. 4 and 5 of the drawings. Adapted to be connected to either side of the swiveled T connection 31, depending upon which side of the apparatus the fluid medium connections are made to the heating coil 18, is a suitable flexible drain hose 33 which extends through a suitable opening 32 in the skirt 10'. It will be understood that a duplicate opening 32 may be provided in the skirt 10' on the other side of the tank 10 if it is desired to have the connections for the drain hose and the heating coil 18 brought in on the side opposite that shown in the drawings. A suitable plug 34 is provided to close the opening in the swiveled T connection 31 not connected to the hose 33. A spring clip or suitable fastening means 35 is provided to hold the nozzle end 36 of the drain hose 33 in a position above the liquid level 21 in the chamber 11 at all times except when it is desired to drain the liquid from this chamber. In certain applications it may be desirable to dispense with the drain hose and merely employ a drain plug to close the drain opening. Such an arrangement is shown in Fig. 7 of the drawings.

In accordance with the present invention, one or more article containers 37 are provided for the textile fabric articles to be weatherproofed. Two such containers are shown in Fig. 2 of the drawings. It will be understood that such article containers may comprise any suitable container having foraminous or perforate walls. As illustrated in the drawings, each article holder or basket comprises a pair of end members 38, each provided with a hand hole 39 and a centrally positioned trunnion 40, the purpose of which will become apparent from the following description. The end members 38 are interconnected by four rods 41 disposed at the corners thereof and fastened thereto by suitable means such as threaded extensions of the rods 41 extending through openings in the end pieces 38 and to which are applied suitable nuts 42. In order to complete the article container or basket, the space between the four rods 41 is enclosed by spaced rods 43 which extend into suitable recesses formed in the end plates 38. With this arrangement, a suitable basket or article container is provided which will hold any textile fabric article and yet will permit the impregnating fluid to freely enter the basket when the basket or container is immersed in the fluid containing chamber 11. The basket construction described above provides a very sturdy article container which will stand rough usage and abuse without damage thereto. It should be understood, however, that the article containers 37 may be constructed in many different ways

as far as the present invention is concerned and the illustrated embodiment is by way of example only.

In accordance with one embodiment of the present invention, one of the sections 11a or 11b of the fluid chamber 11 may be considered to be the soaking or immersing chamber. As illustrated in the drawings, the section 11a is the soaking chamber and is provided near the lower portion thereof and just above the heating coil 18 with inclined ledges 45 which may comprise angle iron members or the like suitably fastened to the side walls of the fluid chamber 11 as by welding or the like. These inclined ledges or shelves are inclined toward the dividing partition 26 and are adapted to be engaged by the end pieces 38 of the article container 37 to support it in the fluid chamber section 11a in the manner clearly indicated in Fig. 4 of the drawings. It will be observed that when in this position, the article container 37 is substantially completely immersed in the fluid impregnant so that the textile fabric articles contained therein may be soaked for the desired time and impregnated with the water-repellent material. The fluid chamber 11 is sufficiently wide so that the basket 37 including the trunnions 40 amply clear the side walls thereof in the manner clearly shown in Fig. 3 of the drawings.

In order to manipulate the basket or article container 37 so as to remove it from its soaking position as indicated in Fig. 4 of the drawings without having to touch either the basket, the impregnated articles or the impregnant, there is provided a basket moving device which comprises a rotatable shaft 47 mounted in suitable bearings 46 above the central partition 26 and adjacent the top of the fluid containing chamber 11. Suitable bearing means are provided for rotatably supporting the shaft 47 at either end thereof. Associated with the shaft 47 are a pair of basket transferring arms or cranks 48 each having a trunnion engaging or receiving notch 49. The trunnion receiving notches are angularly related to the crank arms 48 as best shown in Fig. 4 of the drawings, the purpose of which will become apparent from the following description. The cranks 48 may be fastened to shaft 47 in any suitable manner such as by welding or the like and are preferably positioned just inside of the bearings 46. In order to rotate the crank supporting shaft 47, one end of the shaft is connected to a suitable gear mechanism 50 mounted within a gear housing 51. Operation of the gear mechanism 50 and consequently rotation of crank supporting shaft 47 is obtained by operation of a hand wheel 53 fastened to a rotatable shaft 54 which extends into the gear casing 51. The end of the shaft 54 adjacent the hand wheel 53 is supported by a suitable member 55 fastened to the rectangular structure 10. When the operator actuates the hand wheel 53, rotation of crank shaft 47 occurs. The casters 15 provided with the non-swiveled connection are mounted at the end of the structure 10 beneath the hand wheel 53 so that actuation of hand wheel 53 will not cause any movement of the device 9.

As shown in Fig. 4 of the drawings, the angular trunnion receiving slots 49 in the cranks 48 cooperates with the inclined basket supporting ledges or shelves 45 in a manner such that gravity tends to move the basket or tank in a direction to hold the trunnions 40 in the trunnion receiving notches 49. When the hand wheel 53 is rotated to produce rotation of the crank shaft 47, the

basket or article container 37 is moved out of section 11a of the fluid chamber 11 and swung over above section 11b of the fluid containing chamber 11. Adjacent the upper part of section 11b of the fluid chamber 11 there are provided inclined basket supports 57 which are substantially identical with the basket supports 45 except that instead of being inclined toward the center of the chamber 11 or in other words, toward the partition 26, they are inclined toward the adjacent end wall so that gravity will tend to move the basket 37 when positioned on the ledges 57 away from the partition member 26 instead of toward it as is the case in soaking chamber 11a. It will be observed that when the crank 48 is rotated through an angle of substantially 180 degrees, the angular trunnion receiving slots 49 of the cranks 48 are positioned so that gravity tends to move the basket 37 and consequently the trunnions 40 out of the trunnion receiving notches 49, whereby the cranks 48 may be returned to their original positions in the soaking chamber 11a as shown in Fig. 4 of the drawings and the basket 37 remains on the ledges 57. This position of the basket 37 as indicated on the right-hand side of Fig. 2 of the drawings is what may be termed the basket draining position in which the excess impregnant is permitted to run back into the section 11b of the fluid containing chamber 11.

It will be observed that as the basket 37 is moved out of the soaking section 11a of the fluid containing chamber 11, the liquid level in this particular compartment will be lowered considerably below the liquid level in section 11b. This causes a swishing and flow of liquid from section 11b into section 11a, thus effectively agitating the impregnant without using the agitator 23. If desired, this agitation of the liquid may be increased by moving the basket into and out of contact with the liquid several times. While the textile fabric articles in the basket 37 are draining on the ledges 57, a second basket 37 can be loaded with articles to be impregnated and immersed in the soaking chamber 11a in the manner shown in Fig. 4 of the drawings.

Generally the soaking operation takes considerably less time than the draining operation. To speed up the entire process, it may be desirable to employ two baskets with a first and a second draining position. Following the soaking operation the basket can be moved out of the soaking chamber to clear the liquid where it is permitted to drain in this first draining position. After the other basket is removed from the second draining position on the ledges 57 then the basket in the first draining position may be moved to the second draining position so another soaking operation can take place.

Preferably the tank or structure 10 is provided with a suitable removable cover 60 having a peripheral flange extending around the outside edge of the upper portion of tank 10. This cover may have the form of the cover shown in Fig. 7 of the drawings or if desired, it may be provided with a pair of handles 61 and a deformed rim 62 or a beaded attachment to define a chamber in the top of the cover which may be used to contain spotting liquid as shown in Fig. 1 of the drawings. In other words, the lid or cover 60 may be used as a spotting board. The deformed ridge or beaded portion 62 is preferably discontinuous for a small section as indicated at 63 which acts as a drain opening for the spotting liquid chamber. Preferably the spotting liquid drains off continuously through the drain 63. This may be accom-

plished either by pitching the cover 60 or the entire machine 8 slightly to cause the spotting liquid to flow toward the drain 63.

In view of the detailed description included above, the operation of the machine or device 8 of the present invention will be obvious to those skilled in the art. Briefly summarizing, the fluid containing chamber 11 is first filled to the level 21 with the water-repellent material blended in a suitable solvent such as naphtha or the like and the agitator 23 is periodically operated to maintain the water-repellent material in proper solution. A heating medium is supplied to the coil 18 and when the proper temperature is obtained, the weatherproofing operation may be carried out. One of the baskets 37 is filled with the textile fabric articles to be impregnated and with the cranks 48 positioned so that the notches 49 are above the liquid level 21, the basket 37 is positioned to bring the trunnions 40 into seating engagement with these notches without the operator's hands contacting the impregnating liquid. The crank 53 may now be manipulated to rotate the crank arms downward and thus lower the basket 37 into the soaking chamber 11a so that the articles contained therein are submerged in the fluid or impregnant. As the basket 37 engages the inclined ledges 45, gravity tends to move the trunnions 40 into engagement with the trunnion receiving notches 49, thus preventing the trunnions and notches from becoming disengaged. The basket containing the articles to be impregnated is permitted to remain in the soaking chamber 11a a sufficient length of time to carry out the impregnating process. When this time has elapsed, the operator rotates the hand wheel 53 to swing the arms 48 in an upward direction until the basket clears the liquid in the soaking chamber. The basket is permitted to remain in this first or pre-draining position for a predetermined time. Then the arms 48 are operated to move the basket 37 to the second draining position above the compartment or section 11b where the basket 37 is deposited on the ledges 57. Gravity tends to move the basket 37 along the ledges 57 to facilitate disengagement of the trunnions 40 from the trunnion receiving notches 49. As the crank arms 48 are now rotated back to their initial positions, the basket 37 remains on the ledges 57 in the second draining position where excess liquid drains back into the section 11b of the chamber 11. The flow of liquid caused by removal of the basket 37 from the soaking chamber 11a causes agitation of the solution due to the swishing action of the fluid underneath the partition or baffle 26. While the clothes or textile fabric articles in basket 37 on ledges 57 are draining, a second basket 37 may be filled with articles to be waterproofed and lowered into the soaking chamber 11a in the manner described above. By virtue of the use of two baskets in this manner, the output of a single unit is doubled and in no case must the operator touch either the impregnated clothes or the impregnating solution. Furthermore, a very simple, inexpensive and compact arrangement is provided. The basket 37 may be used to carry the impregnated fabric articles from the second draining position to a suitable spinner or centrifugal extractor so that the operator does not contact the impregnated articles.

In accordance with a modification of the present invention, the second basket 37 may be dispensed with and the device may still operate with the same high output as with the double basket arrangement. As illustrated in Fig. 6 of the

drawings, a suitable tray 65 is positioned on the ledges 57. This tray 65 is illustrated as a wire basket or any other relatively low perforate container. The corresponding parts of Fig. 6 are designated by the same reference numerals as in the preceding figures. In order that the textile fabric articles contained in the basket 37 when in the soaking chamber 11a may be deposited in the tray 65 without requiring the operator to touch either the articles or the solution or the basket, the crank arms 48 are provided with a plurality of threaded openings which are aligned with threaded openings in the end pieces 38 of the basket 37. Suitable studs or pins 66 may be inserted in the openings in the transfer arms or cranks 48 when aligned with the openings in the end pieces 38 of basket 37. It will be obvious that when the transfer arms or cranks 48 are rotated with the crank shaft 47 with the studs or pins 66 in position, the basket 37 will be inverted as it moves over chamber section 11b in the manner clearly shown in dotted lines in Fig. 6 of the drawings so that the textile fabric articles contained therein will be dumped or transferred to the tray 65 where the articles may drain in the same manner as if they were permitted to remain in the basket 37 on the ledges 57. The single basket 37 is now free to be used in soaking a second batch of articles in the soaking chamber 11b.

It is sometimes desirable to provide a device of the type described above for use in connection with relatively small cleaning establishments where the amount of liquid in the soaking chamber need not be so great. In such a case, the device described above can be substantially cut in half by eliminating all but a very small portion of the section 11b. It is desirable to retain some of section 11b together with the partition 26 partially separating it from the section 11a in order to get the swishing action under the baffle plate or partition 26 for increased agitation of the impregnating solution. With such an arrangement the amount of liquid impregnant required is substantially reduced to one half. Of course, the speed of operation of carrying out the impregnating process is reduced since only the pre-draining or first draining position is available for draining the clothes or textile fabric articles following a soaking operation.

In accordance with a modification of the present invention, there is provided a device which uses substantially half of the impregnating liquid that is required in connection with the arrangement described thus far and yet wherein both the predraining or first draining position and the second draining position are provided so that the device may be operated at high speed. Such an arrangement is shown in Figs. 7 and 8 of the drawings where the impregnating device generally designated at 70 is substantially like the device described above except that the tank structure is materially reduced in size to the extent that the section 11b is greatly reduced in size as clearly shown in Fig. 8 of the drawings. It should be understood that the function of chamber 11b is still retained, however, in that it is separated by the baffle 26 not shown in Fig. 8 from the chamber 11a to permit the agitation feature described in detail above. The corresponding parts of Figs. 7 and 8 of the drawings are characterized by the same reference numerals as in the preceding figures.

In order that there is provided a draining position for the device such that the soaking chamber can be used for a subsequent soaking opera-

tion while the textile fabric articles are draining, the device 70 is provided with an extension 71 projecting from only a small upper portion of the main body of the device 70. Mounted within this projection 71 are the ledges 57 identical with the ledges characterized by the same reference numerals in the preceding figures. The extension 71 is of sufficient size so that a basket or article container 37 may be positioned thereabove and any fluid or liquid drained therefrom runs down an inclined bottom 72 of the extension 71 whereby this fluid is returned to the chamber 11b and therethrough the passageway 11c beneath the baffle 26, not shown, to the soaking chamber 11a. As was mentioned above, no casters are provided for the device 70 indicated in Figs. 7 and 8. The drain hose has been dispensed with and only a simple plug 73 for draining the liquid is provided.

As was mentioned above, the cover of the device 70 may be used advantageously as a spotting board. Instead of providing the beaded arrangement described above, however, the cover 74 in Fig. 7 of the drawings which is provided with a peripheral flange is merely inverted when used as a spotting board with the peripheral flange confining the spotting liquid. A suitable depression and drain arrangement 75 at one end thereof permits continuous flow of the spotting liquid in the desired manner described in connection with the cover 60. In order to insure this flow through the drain 75, the cover may either be slightly pitched on the device 70 or the entire device may be raised at one end, for example, the end with which the hand wheel 53 is associated. Any suitable means for supporting the cover 74 in its position to function as a spotting board may be provided. Such means have not been shown in the drawings.

While there have been described certain particular embodiments of the present invention, it will be obvious to those skilled in the art that various changes and modifications may be made without departing from the present invention, and it is aimed in the appended claims to cover all such changes and modifications as fall within the true spirit and scope of the invention.

I claim:

1. A soaking device for textile fabric articles comprising, a fluid containing chamber, an article container including a supporting trunnion at either end thereof, a pair of arms pivotally mounted within said chamber each including a trunnion receiving notch for engaging the trunnions on said container for supporting the same and moving it out of said chamber, and an inclined support for said container positioned within said chamber near the bottom thereof, the notches in said arms when supporting said container within said chamber having their open edges directed toward the higher end of said inclined support so that gravity acting on said container and tending to move it toward the lower end of said inclined support also tends to maintain said trunnions within said notches when said container is disposed on said support within said chamber.

2. In a device for immersing textile fabric articles in a suitable fluid comprising, a fluid containing chamber, a perforate basket for said articles, a shaft pivotally mounted within said chamber, means for rotating said shaft, a pair of transfer arms rotatable with said shaft from a position in said chamber to a position outside said chamber, means including trunnions on said

basket and notches in said arms for releasably fastening said basket to said arms to move said basket out of said chamber, inclined support means on said device for receiving said basket when it is moved out of said chamber, said notches having their open ends directed toward the lower end of said inclined support means when rotated outside said chamber to cause said trunnions automatically to move out of said notches in response to movement of said basket down said inclined support means when said basket is deposited on said support means.

3. A soaking device for textile fabric articles comprising, a fluid containing chamber, an article container including a supporting trunnion at either end thereof, a pair of pivotally mounted arms supported for movement into and out of said chamber each including a trunnion receiving notch for engaging the trunnions on said container for supporting the same and moving it out of said chamber, a first inclined support for said container positioned near the bottom of said chamber, the notches in said arms when supporting said container within said chamber having their open edges directed toward the higher end of said first inclined support whereby the tendency of said container to move downwardly on said first inclined support moves said trunnions into said notches when said container is disposed on said first support, and a second inclined support for said container when it is moved by said arms out of said chamber, the notches in said arms when said arms are outside of said chamber having their open ends directed toward the lower end of said second inclined support whereby the tendency of said container to move downwardly on said second inclined support moves said trunnions out of said notches when said container is disposed on said second support.

4. In a device for impregnating textile fabric articles with a water-repellent material, a liquid containing chamber, a partition dividing the upper portion of said chamber into a pair of sections, interconnected near the bottom of said chamber, one of said sections being a soaking section, a heating coil positioned near the bottom of said chamber, a container for said fabric articles, means for supporting said container in said soaking section substantially submerged in said liquid so that said fabric articles are soaked with said liquid, means for moving said container out of said soaking section and above the other of said sections of said chamber, means for supporting said container above said other section so that excess liquid may return to said chamber, said means removal of said container from said soaking section causing a rush of liquid from said other section to said soaking section thereby agitating said liquid, and additional means for agitating said liquid comprising a movable agitator having the agitating portion thereof disposed beneath said partition and extending partially into each of said sections.

5. In a device for immersing textile fabric articles in a suitable fluid comprising, a fluid containing chamber, an extension projecting from the upper part of said chamber defining a draining section, a perforate basket for said articles, a pivotally mounted shaft supported above said chamber, means for rotating said shaft, a pair of transfer arms rotatable with said shaft from a position in said chamber to a position above said draining section, means including trunnions on said basket and notches in said arms for releasably fastening said basket to said

arms to move said basket out of said chamber, and inclined support means mounted in said draining section for receiving said basket when it is moved out of said chamber, said notches having their open edges directed toward the lower end of said inclined support means when said arms are moved over said draining section whereby the tendency of said basket to move down along said inclined support means when deposited thereon releases said basket from said arms. 10

6. In a device for immersing textile fabric articles in a suitable fluid comprising, a fluid containing chamber, an article container capable of being disposed in said chamber, a shaft pivotally mounted within said chamber, means for rotating said shaft, a pair of transfer arms rotatable with said shaft from a position in said chamber to a position outside said chamber, a support means on said device for receiving said container when it is moved out of said chamber, said support means being disposed at an angle to the horizontal, cooperating means on said arms and said container for releasably fastening said container to said arms, the portion of said last mentioned means associated with said arms and the angular disposition of said support means co- 20

operating to cause said container to move free of said arms when said container is deposited on said support means.
